DESIGN FOR A LAMP BASE

Harry Gogolick, Brooklyn, and Elliott Meyer,
New York, N. Y.

Application July 29, 1946, Serial No. 132,082

Term of patent 3½ years

(Cl. D48—20)

To all whom it may concern:

Be it known that we, Harry Gogolick and Elliott Meyer, citizens of the United States of America, residing in the Borough of Brooklyn, city of New York, county of Kings, and State of New York, and Borough of Manhattan, city of New York, county of New York, and State of New York, respectively, have invented a new, original, and ornamental Design for a Lamp Base, of which the following is a specification, reference being had to the accompanying drawing, forming part thereof:

We claim:

The ornamental design for a lamp base, as shown.

HARRY GOGOLICK.
ELLIOTT MEYER.
